UNITED STATES PATENT OFFICE.

ALDON FENTON THOMPSON, OF CONYERS, GEORGIA.

COMBINATION LEDGER AND INDEX.

No. 840,175.

Specification of Letters Patent.

Patented Jan. 1, 1907.

Application filed May 12, 1904. Serial No. 207,661.

To all whom it may concern:

Be it known that I, ALDON FENTON THOMPSON, a citizen of the United States, residing at Conyers, in the county of Rockdale and State of Georgia, have invented a new and useful Combination Ledger and Index, of which the following is a specification.

This invention relates to a combination ledger and index.

10 The object of the invention is to improve the indexing facilities of ledgers and other account-books.

With the foregoing and other objects in view, which will appear as the description 15 proceeds, the invention resides in the combination and arrangement of parts and in the details of construction hereinafter described and claimed, it being understood that changes in the precise embodiment of invention here- 20 disclosed can be made within the scope of the following claims without departing from the spirit of the invention or sacrificing any of its advantages.

In the accompanying drawings, forming 25 part of this specification, Figure 1 is a perspective view of a ledger constructed in accordance with the invention. Fig. 2 is a plan view showing the arrangement of the index and ledger sheets. Fig. 3 is an en- 30 larged detail view of an index-sheet; and Fig. 4 is a perspective view of a portion of the ledger and index and showing the spaced relation of the tabs, the "A" set of sheets being removed.

35 Like reference characters indicate corresponding parts in the different figures of the drawings.

In arranging a ledger according to the present invention it is proposed to employ a set 40 of ledger-sheets adapted to receive a number of accounts coming under the same index-letter. For example, a certain number of ledger-sheets will be arranged to receive accounts coming under the letter "A," a second set of sheets will be arranged to receive the "B" accounts, a third set to receive the "C" accounts, &c. The index-sheet for the "A" accounts will be preferably arranged between the "A" and "B" sets of sheets. The 45 index-sheet for the "B" accounts will be arranged between the "B" and "C" sets of sheets, &c.

Referring to Fig. 1 of the drawings, the reference-numerals 1 indicate a plurality of index-sheets, and the reference-numerals 2 indicate a plurality of sets of ledger-sheets,

the index-sheets being alternately arranged with respect to the sets of ledger-sheets. Beginning at the left-hand side of Fig. 1, the numeral 2 indicates the set of sheets which 60 are to be used for accounts coming under the letter "A." In the embodiment of invention illustrated this first set of ledger-sheets will consist of any number of sheets running from twelve to twenty-two. The first set of 65 sheets for the letter "A" will be provided with a set of tabs 2^a, which may be provided with numbers running from "1" to "22." The set of tabs 2^a preferably is produced by cutting away the first sheet down to the line 70 2^b, the second sheet down to 2^c, the third sheet down to 2^d, so that each succeeding sheet will be cut away far enough down to expose a small portion of the preceding sheet 75 sufficiently to adapt the same to receive a number or other character—such, for example, as the series of numbers "1" to "22," inclusive, (indicated by the numeral 6 in Fig. 2.) The first index-sheet 1 at the beginning of the ledger is arranged at the end of 80 the first set of ledger-sheet 2—that is to say, the first index-sheet 1 is placed next to the last sheet of the set which bears the tab numbered "22." The index-sheet 1, which preferably is arranged as shown in Fig. 3 of 85 the drawings, is placed in the ledger so that its outer edge 1^a will be disposed along the inner edge of the series of tabs "1" to "22" of the first set of ledger-sheets 2. Arranged along the outer edge 1^a of each index-sheet 1 90 is a set of numbers 10, which correspond with the numbers on the adjacent set of tabs of the preceding set of ledger-sheets 2. Each of the index-sheets 1 preferably is 95 ruled, as shown in Fig. 3, so as to be provided with two sets of vertical columns A' and B', each set consisting, preferably, of twenty-seven columns, so that twenty-six of the columns can be provided at their upper and lower ends with the letters of the alphabet, and the twenty-seventh column can be employed for a purpose hereinafter to appear. When a name is indexed in the set of columns A', the bookkeeper will know that when the ledger is opened to the proper ledger-sheet the account will appear on the left-hand side of the book, and when an account is indexed in the set of columns B' the bookkeeper will know that it will appear on the right-hand side of the ledger when it is 105 opened to the proper place. In addition to the vertical columns each index-sheet is pro-

vided with horizontal lines, which extend across from the numbers "1" to "22" on the margin 1^a of the sheet, as shown. When entering an account which occurs under the letter "A," the bookkeeper will first select one of the ledger-sheets of the first set of sheets 2. In the embodiment of invention shown it is intended that the bookkeeper shall first use the regular ledger-sheets having the tabs numbered from "5" to "18." After having selected a blank sheet occurring between the numbers "5" and "18" the bookkeeper enters the account. If, for example, he has selected the ledger-sheet bearing the tab-number "5," he remembers this number and then turns to the index-sheet for the letter "A." The name of the account is entered on the horizontal line opposite the number "5" on the edge of the index-sheet, so that the first letter of the same will appear in the vertical column which contains at the upper and lower ends thereof the second letter in the name. In order to place the first letter of the name in the proper column, it will be obvious that the succeeding letters of the name will appear on the horizontal line 5 to the right of the second-letter column. In this way when the bookkeeper desires again to turn to the account which he has entered he opens the ledger to the index-sheet "A" by means of the series of index-tabs 13, which are placed on the upper edges of the index-sheets. After having turned to the proper index-sheet he glances down the column of the first vowel of the name for which he is looking. Upon finding the desired name the bookkeeper follows the horizontal line across to the edge of the index-sheet, where he sees the number "5" in the instance given. By then placing his thumb upon the tab numbered 5 of the first set of ledger-sheets 2 he can readily open the ledger to the exact page desired. Then if the name appeared in the set of columns A' of the index-sheet the bookkeeper will look on the left-hand side of the center of the ledger to find the account, and if it appeared in the set of columns B' he will look on the right-hand side of the center of the ledger. In this way it will be apparent that any account can be turned to with great facility.

Having now described the arrangement of the first set of ledger-sheets 2 and briefly outlined the method of using the index, a description will now be given of the second set of ledger-sheets, which in the embodiment of invention illustrated will be employed for the accounts coming under the letter "B a-o." To avoid confusion, the set of leaves marked on the drawings "B a-o" will be referred to in the following description as the sheets for the letter "B" merely.

The second set of ledger-sheets 2' for the letter "B" follows the index-sheet 1 for the letter "A." The sheets comprising the second

set of ledger-sheets preferably are provided along their margins with a set of tabs 3^a, which are numbered, preferably, from "1" to "18," as shown. The sheet containing the tab 18 is the next sheet after the index-sheet 1 of the first set of ledger-sheets 2 for the letter "A." The tabs 3^a on the second set of ledger-sheets 2' preferably are formed by cutting away the lower outer edge of the sheet containing the tab 18 up to the line 75 marked 3^b. In this instance the tab containing the number "18" also contains the number "17," as two numbers, such as "17" and "18," can be allotted to a single ledger-sheet 2' whenever desired. The next adjacent tab, containing the numbers "15" and "16," is formed by cutting the following sheet up to the line 3^c, the remaining tabs being similarly formed by cutting each succeeding sheet upward a little higher, as 80 shown. The index-sheet 1' for the second set of ledger-sheets—that is, the index-sheet for the ledger-sheets containing the "B" accounts—follows the sheet 2', which contains the tab numbered "1." This second index-sheet 1' is exactly the same as the index-sheet previously described, and illustrated in Fig. 3.

It may be here explained that each of the index-sheets is divided into a plurality of 95 sections, preferably by means of the heavy horizontal lines 30 and 31, the line 30 being arranged above the fifth horizontal line and the line 31 being arranged below the eighteenth horizontal line, as shown. By reason 100 of the fact that the first set of tabs 2^a for the first set of ledger-sheets 2 begins at "1" and runs down to "22" and by reason of the fact that the second set of tabs 3^a for the second set of ledger-sheets 2' runs down only to 105 "18" it will be obvious that the lower end of the first set of tabs 2^a extends downward beyond the second set of tabs 3^a, so that while the second set of tabs 3^a, running from "1" to "18," will normally cover and 110 conceal the tabs numbered from "1" to "18" of the first set 2^a the lower portion of the first set of tabs 2^a—that is, the tabs running from "19" to "22"—will extend beyond the lower end of the second set of tabs 3^a, so as 115 not to be concealed thereby. This peculiar arrangement of the second set of tabs 3^a, so that it starts at a point removed from the lower end of the set of tabs 2^a, constitutes a valuable improvement of the present invention in that it permits the lower section of the second index-sheet 1'—that is, the section below the horizontal line 31—to be disposed along the edge of the tabs 19 to 22 of the first set of tabs 2^a.

As previously explained, the bookkeeper when he begins to open his "A" accounts uses the ledger-sheets containing the tabs numbered from "5" to "18" and indexes the names upon the horizontal lines numbered 120 130

"5" to "18" on the "A" index-sheet. If we suppose now that all the "A" ledger-pages containing the tabs running from "5" to "18" have been filled with accounts, the bookkeeper can first use the "A" ledger-pages containing the tabs numbered from "1" to "4." After these pages from "1" to "4" have been filled with "A" accounts the bookkeeper can next use the "A" ledger-pages containing the tabs numbered from "19" to "22." Each time an account is entered upon one of the "A" pages containing the tabs numbered from "19" to "22" the bookkeeper can immediately turn to the "A" index-sheet 1 and index the name on the horizontal line corresponding with the number on the tab of the "A" ledger-sheet which he has selected. Suppose, however, that in some portion of the country there shall be more "B" accounts than "A" accounts. In this case it will be found that the bookkeeper will not have to use the "A" ledger-sheets containing the tabs numbered from "19" to "22." However, after all the "B" ledger-sheets containing the tabs numbered "5" to "18" have been filled with accounts the bookkeeper can turn to the "A" ledger-sheets containing the tabs numbered from "19" to "22" and can fill them with "B" accounts, if desired. Each time a "B" account is entered on the "A" ledger-pages containing the tabs numbered from "19" to "22" the bookkeeper turns to the "B" index-sheet and enters the name on the proper horizontal line corresponding with the number of the tab of the "A" ledger-page which he has used. By reason of the fact that the "B" tabs 3^a are cut away below the tab numbered "18" it will be obvious that the lower portion of the "B" index-sheet 1', containing the horizontal lines numbered "19" to "22," inclusive, can be caused to fit along the edge of the "A" ledger-sheets containing the tabs numbered from "19" to "22," so that whenever the bookkeeper finds a name entered, for instance, on the horizontal line 20 of the "B" index-sheet 1' he places his finger upon the tab numbered "20" of the set of "A" ledger-pages 2 and immediately opens the book to a "B" account which has been placed in the set of "A" pages. From the foregoing description it will be seen that all of the "A" pages containing the tabs numbered from "19" to "22" can be used for either "A" accounts or "B" accounts without interfering in any way with the index facilities of the improved ledger.

The third set of ledger-sheets for the next set of ledger-accounts is exactly the same as the first set of ledger-sheets 2, excepting that the tabs 4^a thereof are numbered from "5" to "22," inclusive, and the first sheet, which contains the tab 5 and immediately follows the index-sheet 1', is cut away down to the point 4^b, as shown, so that the tabs 1, 2, 3,

and 4 of the ledger-pages 2' will be located above the upper edge 4^b of the third set of tabs 4^a and will not be obscured or concealed thereby. For this reason it will be obvious that the ledger-sheets 2' containing the tabs 1, 2, 3, and 4 can be used not only for receiving "B" accounts which can be indexed upon the upper section of the "B" index-sheet 1' down to the horizontal line 30, but said ledger-sheets can also be used for containing "B r-y" accounts, which will be indexed upon the upper section of the third index-sheet 1'. The fourth set of ledger-sheets for the next letter following "B r-y"—such, for example, as the letter "C"—will be formed with tabs 80 exactly the same as the tabs 3^a on the second set of ledger-sheets 2', and all the other sets of ledger-sheets throughout the book will be formed in the same manner, every other set of tabs being similar, so that one set of tabs 85 will start at a point removed from the end of the next preceding set of tabs, so as to expose a portion of the preceding set of tabs and normally conceal the remainder of said preceding set of tabs. 90

It will be obvious from the foregoing description that the different sets of tabs incline in opposite directions from the front to the rear of the ledger—that is to say, while the sheet containing the tab 1 in the first set of ledger-sheets 2 is nearer the beginning of the book than the ledger-sheet containing the tab 22 still in the second set of ledger-sheets 2' the ledger-sheet containing the tab 18 is nearer the beginning of the book than the ledger-sheet containing the tab 1, and so on through the ledger. 100

Referring to the employment of twenty-seven columns on each index-sheet, it is to be understood that in regular use the letters at the top and the bottom of the sheet indicate the first, second, third, or fourth letter in the surname, depending on the particular system of indexing which it is desired to use. In entering the names on the index-sheets they are written so that the initial letter of the surname comes in the vertical column the letter of which corresponds to the second, third, or fourth letter in the name, according to the number of letters on the index-tag at the top 115 of the index-sheet. The initial letters immediately follow the surname, and in the case of firms the first part of the firm-name is entered as a surname would be. When a number of customers have the same surname, the surname may be written once and the initial preceded by ditto-marks written so that the first initial will come in the column the letter of which corresponds to the second initial. 120 If there be no middle name, the first initial, preceded by ditto-marks, is written on the twenty-seventh column or the given name written so that its initial letter will be in the twenty-seventh column. (See entry of "Camp," &c., Fig. 3.) If the first part of a 125 130

number of firm-names be identical, the first part of the firm-name may be written once, and the second part of the name preceded by ditto-marks written so that the initial letter will come in the column the letter of which corresponds to the initial letter of said second part of the firm-name. (See entry of "Columbus, &c.," Fig. 3.)

The series of tags 13, attached to the top of the index-sheet, begin at the front of the ledger and run toward the back, starting near the center of the sheets and extending outward to the edge where one series ceases and another series begins near the center of the sheet and extending outward as before. Two series or rows of tags are sufficient for an ordinary-sized ledger, the first running from "A" to "M" and the second from "Mc" to "Z." Ordinary tags of regular size attached to the top of a thick book will often be concealed by the top of the ledger-pages, and it will be necessary for the bookkeeper to stoop over in an uncomfortable and tiresome position to be able to see the desired tag. By the manner herein shown of arranging the tags this objection is entirely overcome, as the tags are placed at the top corner of the ledger and at the point habitually handled by bookkeepers. By the manner of printing on the top of the ledger and index sheet included in the series of tags duplicates of the characters on the tags the bookkeeper can instantly locate any desired tag in the series, whether he can see it or not. If he cannot see the desired tag, he reaches over the top of the ledger and places the index-finger of his left hand exactly beneath the duplicate of the top of the ledger-sheet where the tag is found, and the ledger may be opened without any trouble.

The combined ledger and index of this invention will be found thoroughly efficient and durable in use and will overcome a great many difficulties present with the ordinary form of ledgers in use.

At the top and bottom of each of the ledger-sheets 2 the tab-numbers of which are less than "5" or more than "18" is a space 15 and 16,

respectively, which correspond in area to the upper and lower sections 3 and 5 on the index-sheets which are formed by the lines 30 and 31, and upon these sections 15 and 16 of the ledger-sheets are entered accounts when the regular ledger-sheets are full.

What is claimed is—

1. An account-book having a set of pages provided with a set of tabs, an index-sheet arranged adjacent said set of tabs, a second set of pages, a second set of tabs connected with said second set of pages, one end of said second set of tabs being located at a point removed from the end of the first-mentioned set of tabs to expose a portion of said first-mentioned set of tabs and normally conceal the remainder of said first-mentioned set of tabs, and a second index-sheet arranged adjacent said second set of tabs and also adjacent the exposed portion of said first-mentioned set of tabs.

2. An account-book having a set of pages provided with a set of marginal tabs having a series of characters thereon, an index-sheet having a series of characters identical with the characters on said tabs, a second set of pages, a second set of tabs connected with said second set of pages, one end of said second set of tabs being located at a point removed from the end of the first-mentioned set of tabs to expose a portion of said first-mentioned set of tabs and normally conceal the remainder thereof, said second set of tabs being provided with a series of characters, and a second index-sheet having a series of characters identical with the series of characters of the first-mentioned set of tabs, said index-sheet being arranged adjacent the second set of tabs and the exposed portion of the first set of tabs.

In testimony that I claim the foregoing as my own I have hereto affixed my signature in the presence of two witnesses.

ALDON FENTON THOMPSON.

Witnesses:

J. S. THOMPSON,
W. J. EAKES.
